TONE ARM

Bruce Kamp, Springfield, Pa., assignor to The Astatic Corporation, Conneaut, Ohio, a corporation of Ohio

Application June 7, 1956, Serial No. 41,800

Term of patent 7 years

(Cl. D26—14)

Fig. 1 is a perspective view of a tone arm, showing my new design;

Fig. 2 is a perspective view thereof from another position;

Fig. 3 is a side elevational view thereof; and

Fig. 4 is a rear elevational view thereof.

I claim:

The ornamental design for a tone arm, as shown.
